(57) **CLAIM**

The ornamental design for a reflection device, as shown and described.

DESCRIPTION

FIG. 1 is a front perspective view of a reflection device of my new design;

FIG. 2 is a front view of the reflection device thereof;

FIG. 3 is a rear view of the reflection device thereof;

FIG. 4 is a left view of the reflection device thereof;

FIG. 5 is a right side view of the reflection device thereof;

FIG. 6 is a top side view of the reflection device thereof;

FIG. 7 is a bottom view of the reflection device thereof; and,

FIG. 8 is a rear perspective view of the reflection device thereof.

The broken lines shown in the drawings illustrate portions of the reflection device that form no part of the claimed design.
